U. S. PATENT OFFICE.

No. 29.

1861.

WHOLE NO. 1,394.

Carpet.

ELEMIR J. NEY, OF LOWELL, MASS.,
ASSIGNOR TO LOWELL MANUFACTURING CO.

Letters Patent for a Design No. 29, dated March 19, 1861.

SPECIFICATION.

TO ALL WHOM IT MAY CONCERN:

Be it known, that I, ELEMIR J. NEY, of Lowell, in the county of Middlesex and State of Massachusetts, have originated and designed a new Pattern for Carpets or other fabrics, of which the following is a full, clear, and exact description, reference being had to the accompanying drawings making part of this specification.

A in the centre consists of 8 acorns, surrounding a small rosette, and resting on a solid block having 8 radial arms. Corners 1 2 3 and 4, when matched, form a figure similar to A in the centre.

Surrounding the figures of the centre and corners, and enclosing large diamonds on which these figures rest, is the frame B, composed of a Persian style of work.

Small sprigs occupy the corners of the diamonds enclosed by the frame B.

The colors employed for the different portions of the design may be varied to suit the taste and wishes of the manufacturer.

Claim.

What I claim as my invention, and desire to secure by Letters Patent, is—
The design or pattern for carpets, or other fabrics, herein set forth.

E. J. NEY.
